UNITED STATES PATENT OFFICE.

JAMES H. REINHARDT, OF EAST ORANGE, NEW JERSEY, ASSIGNOR TO AMERICAN BANK
NOTE COMPANY, A CORPORATION OF NEW YORK.

NUMBERING-MACHINE.

1,175,559.

Specification of Letters Patent. Patented Mar. 14, 1916.

Application filed February 28, 1914. Serial No. 821,644.

To all whom it may concern:

Be it known that I, JAMES H. REINHARDT, a citizen of the United States, residing at East Orange, in the county of Essex and 5 State of New Jersey, have invented certain new and useful Improvements in Numbering-Machines, of which the following is a specification, reference being had therein to the accompanying drawings, which form a 10 part therein.

My invention relates to numbering machines, and more particularly to a type of such machines wherein the mechanism for actuating the digit wheels of the numbering 15 heads, is so constructed as to avoid the necessity for cutting or channeling the surface of the inking roller. In a machine of this character, it is the ordinary practice to mount a plurality of sets or sequences of 20 independently operative numbering heads upon a rotary drum. The number of heads in each set or sequence and the number of such sets or sequences may vary according to the requirements of the work being done. In 25 such machines, as are now commonly used, the numbering heads are actuated one or more times during each rotation of the drum, by the impact of a plunger carried by each head and projecting beyond the printing 30 face of the characters upon the digit wheels, with one or more fixed abutments, a construction which necessitates the cutting or channeling of the inking roller, and permits only a circumferential adjustment of 35 the numbering heads. Furthermore, the force of the impact is sufficiently great and sharp to cause excessive wear upon the parts of the head, and tend toward a loss of alignment through the overrunning of the digit 40 wheels.

By my present invention, I aim to secure a numbering machine wherein the actuating means for the various numbering heads will be disposed below the printing face of the 45 digit wheels, thus avoiding a construction necessitating the cutting or channeling of the inking roller, while at the same time insuring reliability in the actuation of the numbering heads.

50 By a construction such as that shown in the accompanying drawings and contemplated by my invention, the various numbering heads may not only be adjusted cir-

cumferentially of the axis of the drum, but they may also be adjusted axially thereof by 55 reason of the fact that the absence of a channel in the inking roller avoids a condition wherein the numbering heads must bear a fixed relation to said inking roller. In the type of machine now commonly used, an 60 axial adjustment of the heads necessitates the employment of a new inking roller. Each numbering head of a set or sequence is operated by independently operative actuating means the same means preferably 65 being employed for actuating the corresponding head of other sets or sequences when a plurality of such are used. To permit an equal spacing of the various numbering heads of each set or sequence while 70 at the same time permitting a variance in their spacing, the actuating means must be so constructed that whatever the spacing may be, each numbering head will be brought within the operative range of an 75 actuating means. I also, by my invention, provide means whereby any actuating means may be rendered inoperative if desired.

To prevent the impact of sharp blows 80 upon the actuating plunger of the various numbering heads, the actuating means is placed under the control of a plurality of oppositely disposed cams, the riser or risers of which is or are of a pitch to impart a 85 gradual movement to said plunger after the numbering head to be actuated, has left the printing position, and before it is in the operative relation to the inking mechanism. Preferably these cams are so constructed 90 that the riser portion thereof may be removed and exchanged for a different portion, employing one or more risers according to whether the numbering heads are to be actuated once or a plurality of times 95 upon each rotation of the drum. Inasmuch as the actuating means for the numbering heads always bears a fixed relation to its numbering heads with the exception of that movement thereof under the control of the 100 cams, means must be provided for supporting said actuating means which supporting means will have rotary movement with the drum while at the same time permitting that free reciprocatory movement of the actuating means essential to the timely actua- 105

tion of the numbering heads. To facilitate the mounting of the numbering heads upon the drum, I provide means whereby said drum may be rotated independently of the driving means therefor, interlocking means being provided whereby after the desired adjustment of the drum has been effected said drum may be secured firmly to said driving means in its adjusted position, thus permitting not only the movement of the drum independently of said driving means, but any desired adjustment of the drum with relation thereto. Under some conditions, it is desirable to permit the drum to rotate without a resulting actuation of any of the numbering heads and to meet this condition it is essential that means be provided whereby the cams controlling the actuating means for the numbering heads may be rendered inoperative at the will of the operator, a condition provided for by my invention.

My invention consists primarily in a numbering machine embodying therein a drum adapted to carry a set or sequence of numbering heads, a plurality of numbering heads, mounted thereon, a plurality of independently operative actuating means each acting upon a numbering head and means common to all of said actuating means whereby they are successively operated to actuate their respective numbering heads after leaving the printing position, and before reaching the inking position, and in such other novel features of construction and combination of parts as are hereinafter set forth and described and more particularly pointed out in the claims hereto appended.

40 Referring to the drawings: Figure 1 is a side elevation of a numbering machine embodying my invention; Fig. 2 is a section on the line 2—2 of Fig. 1; Fig. 3 is a section on the line 3—3 of Fig. 1; Fig. 4 is a 45 detailed view of one of the cam mechanisms; Fig. 5 is a section on the line 5—5 of Fig. 1; Fig. 6 is a detailed view of one of the actuating means; Fig. 7 is a section on the line 7—7 of Fig. 1; and Fig. 8 is a detailed view 50 of the means for rendering the cams inoperative.

Like letters refer to like parts throughout the several views.

In the embodiment of my invention shown 55 in the drawings, *a* indicates the frame of a machine, having mounted therein the main shaft *b* driven by the gear *c*. Mounted upon and rotatable with the shaft *b* are a plurality of drums *d*, *d'*, *d''*, *d'''*, and *d⁴* each 60 adapted to carry a set, or sequence, of similar numbering heads *e*. The number of such drums and the number of heads upon each drum may vary. Said drums are capable of being shifted axially of the shaft *b* 65 and said heads are adapted to be shifted

circumferentially of their drums, to permit said heads to be adjusted to adapt the machine for work upon different lots of work.

At *f*, I have shown an impression roller which is cylindrical in form and of the same diameter throughout, the construction of the machine being such that the numbering heads may be actuated by means which will obviate the necessity for cutting or channeling the inking roller or rollers. The impression roller *f* is provided with the usual gripper mechanism *f'*.

Each of the drums *d*, *d'*, *d''*, *d'''*, and *d⁴* has a sequence of circumferentially spaced openings *g*, *g'*, *g²*, *g³*, *g⁴*, *g⁵*, *g⁶*, *g⁷*, and *g⁸*, extending therethrough each of which openings is adapted to receive an actuating mechanism which is operative independently of other similar mechanisms and upon only that numbering head mounted adjacent thereto. Ordinarily a plurality of sets or sequences of numbering heads is employed and hence the openings *g* to *g⁸* of the respective drums should be aligned with each other so that actuating means common to the corresponding numbering head of the different sets or sequences may be used. Mounted in each set of openings *g* to *g⁸* is an actuating bar *h*, *h'*, *h²*, *h³*, *h⁴*, *h⁵*, *h⁶*, *h⁷*, or *h⁸* adapted to have movement radially of said drum and to act upon the plunger *e'* of the numbering head adjacent thereto. As will more fully appear hereinafter these bars are independently operative so that the power required to change or advance the numbering heads will be reduced to a minimum. It will also appear that the movement of said bars will be so gradual as to avoid any sharp impacts while insuring a timely actuation of the numbering heads.

Supporting the several actuating bars *h* to *h⁸* are a plurality of disks *j*—*j'* mounted upon and rotatable with the shaft *b* so as to have movement with the various drums, said disks having therein radial slots adapted to receive the stems of the bars *h* to *h⁸* so as to permit the free reciprocatory movement of said bars and at the same time relieve the various drums from any strains from said actuating means. Each of the disks *j*—*j'* is provided with a sequence of radial slots *k*, *k'*, *k²*, *k³*, *k⁴*, *k⁵*, *k⁶*, *k⁷*, and *k⁸* and openings therethrough adapted to permit the insertion or removal of the enlarged heads of said bars. The said openings are indicated by the references *l'*, *l²*, *l³*, *l⁴*, *l⁵*, *l⁶*, *l⁷*, and *l⁸*.

To facilitate the circumferential adjustment of the numbering heads *e* upon their drum, I provide each actuating bar with a circumferentially extending enlarged head *i*, *i'*, *i²*, *i³*, *i⁴*, *i⁵*, *i⁶*, *i⁷*, or *i⁸*, the outward or contact surface of which extends upon a curve concentric with the periphery of the drum. To adapt the machine to different

classes of work necessitating a different spacing of the numbering heads in each set or sequence, the openings g to g^s and l to l^s and the heads i to i^s vary in length as shown.

5 Mounted adjacent the disk j is a cam m and mounted adjacent the disk j , is a cam n , the ends of the respective bars h to h^s projecting beyond said disks and carrying anti-friction rollers coöperating with said 10 cams respectively. Normally these cams have a fixed relation to the drum, although, as will appear hereinafter means are preferably provided whereby said cams may be permitted to rotate with said drums and the 15 shaft b so as to permit the actuation of the machine without a resulting change of the numbering heads.

In the use of the numbering machines, it is sometimes necessary to "skip" or change 20 the numbering heads two or more times with each rotation of the drums and to meet this condition I so construct the cams $m-n$ that one or more risers may be used according to the number of times it is desired to actuate 25 the numbering heads with each rotation thereof. This construction, as shown more particularly in Figs. 3 and 4, comprises a sectional cam, the main part of which has a segmental groove m' , concentric with the 30 axis of the cam, and an extension m^2 having an opening m^3 therethrough which opening is adapted to permit the removal or assembly of any of the actuating bars h to h^s . Detachably secured to said extension m^2 is a 35 removable cam section m^4 having a groove therein containing one or more risers m^5 and m^6 . This removable section has a bearing 40 therein adapted to straddle the shaft b , said bearing opening outwardly so as to permit the mounting or demounting of said section upon said shaft. Means as the bolt holes m^7 are provided by means by which said section may be firmly secured to the main body of 45 the cam. Pivottally mounted upon the section m^4 is a swinging member m^8 carrying a closure plate m^9 adapted to enter the slot m^{10} in the section m^4 and close the opening m^3 . The section m^4 is provided with an 50 opening m^{11} adapted to register with the opening m^3 . The swinging member m^8 forms the outer surface of a portion of the cam groove.

To permit the turning of the drums independently of the main gear c , I provide 55 said gear with a disk o having a series of screw-threaded openings as o' , o^2 , o^3 , o^4 , o^5 , o^6 , o^7 , o^8 , and o^9 , therein; and mount the gear c loosely upon the shaft b . To make 60 this gear operative, it is connected to said disk as by means of the screw bolt p passing through an opening in the gear and coöperating with any of the openings o' to o^9 . It will thus be observed that by removing the bolt p , the shaft b carrying the various 65 drums may be turned to any desired extent,

the openings o' to o^9 permitting it to be locked with relation to the gear c in any position which will bring an actuating bar directly below the printing point of the impression roller.

It quite frequently happens that it is desirable to prevent the actuation of the numbering heads while the machine is running, and to meet this condition, I provide means for normally preventing rotary movement 70 of the cams $m-n$, or in other words, for holding them in a fixed position relative to the drums d to d^4 , which means, however, are operative to release said drums and permit the free rotation thereof. To secure the 75 desired results this means must be so constructed that when it is desired to again actuate the numbering heads, its movement may be such as to so position the risers of the cams as to insure a timely actuation of 80 the numbering heads. In the form of the invention shown, this mechanism comprises the stop levers q , each having a stop arm q' adapted to be projected into the path of a stud r carried by each cam m or n . These 85 levers are adapted to be actuated by a link s which may be controlled in any desired manner. To minimize the effect of the impact of the studs r with the stop arms q' , I mount upon each lever q a compressible spring projected retard t adapted to be engaged by a stud r and bring the cam to a gradual stop 90 upon this engagement with the stop arm q' . The end of this retard is spaced away from the arm q' sufficiently to hold the cams 95 firmly in position except when the levers q are actuated to release the cams. The inking mechanism is shown conventionally at u .

The operation of the herein described machine is as follows: Assuming that the machine has been properly set for a run, power is applied to the shaft b by the gears c through the disk o . In turning, the shaft b will carry with it the disks $j-j'$ and all of the drums d , d' , d^2 , d^3 , and d^4 , and any 100 other number of drums which may be mounted upon said shaft. The various bars h , h' , h^2 , h^3 , h^4 , h^5 , h^6 , h^7 , and h^8 will also be carried around with the disks $j-j'$, the 105 relation of said bars to their respective numbering heads e and all numbering heads upon corresponding radii or the respective drums, remaining constant. The cams $m-n$ remaining fixed, the various rollers carried by said bars will travel in the groove of 110 said cams and impart a reciprocatory movement to said bars at a time and to an extent determined by the position and configuration of the risers of said cams. As each 115 row of numbering heads approaches the inking mechanism, these rollers will ride upon a circular portion of the cams, thus permitting inking of the digit wheels just prior to making of an impression and preventing movement of said digit wheels until after 120

such imprint has been made. After the making of the imprint the continued rotation of the drums d to d^4 and disks $j-j'$ will bring the antifriction rollers of said bars into engagement with the riser or risers of the cam, thus imparting thereto one or more reciprocations sufficient to actuate the numbering heads. The bars h , h' , h^2 , h^3 , h^4 , h^5 , h^6 , h^7 , and h^8 will be brought into operative relation to the riser or risers of the cams successively, so that the numbering heads will be actuated one row at a time and each row will be actuated independently of every other row. This actuation of the numbering heads will occur after the making of the imprint and before the numbering heads reach the inking mechanism. If it be desired to make any actuating means inoperative, this result may be secured by removing the rollers from the bar and if desired the entire bar may be removed from this relation to the drums through the opening in either disk j or j' and either cam m or n . The enlarged heads i to i^8 of the bars h to h^8 being between the disks $j-j'$, they are free to reciprocate, the stems of said bars being guided by the slots in said disks. The drums d to d^4 being adjustably set upon the shaft b , a lateral or axial spacing of the numbering heads may be secured by merely shifting the drums along the shaft and keying or clamping them in position. To adjust the heads circumferentially of the drums is more difficult, however. To meet this condition, the heads i to i^8 are successively increased in circumferential length thus permitting the differential spacing of succeeding heads to compensate for the cumulative movement necessary to preserve equality of the spaces between succeeding heads. The machine shown in the drawings is designed to accommodate five heads only, and with the arrangement of actuating bars shown, any desired spacing may be secured. If the spacing between succeeding heads be so great that any one head will not be within the operative range of one of said bars, the bolt may be removed, and the disk o turned, carrying with it the drums d to d^4 and disks $j-j'$, until the desired bar is below the print in position whereupon the bolt p is replaced. This shifting of the drums preserves the proper timing of the actuation of the numbering heads with relation to the printing interval. Furthermore, the shifting of the actuating bars varies the position of the heads i to i^8 with relation to the cams $m-n$ and presents different areas of contact surface, so that the numbering heads may be differently spaced and yet be within the operative range of one of said bars. For example, if it be desired to increase the distance between succeeding numbering heads e , the one acted upon by the bar h would be moved to the left, Fig. 2, to an amount equalizing the desired increase. The numbering head acted upon by the bar h' would not be disturbed. The numbering head acted upon would be moved to the same extent as the first head e but in the opposite direction. The succeeding head would be moved twice the distance of the last named head, while the fifth head would be moved three times that distance. Hence if one of the heads, for instance, the fourth, when moved would not be positioned above the bar h^3 , but between it and the bar h^4 , it would be necessary to shift the bars so that the first head would be acted upon by the bar h^2 , the different spacings and dimensions of the heads of the bars being such that one of said bars would act upon each head. The heads i to i^8 are made of different lengths because of the different quantities of movement of succeeding heads in effecting a change of the spacings thereof. If it be desired to increase the number of numbering heads, the drums may be rotated so that the desired spacing of the desired number of heads can be secured, although two heads e might come within the operative range of a single actuating bar. This, while not entirely desirable, is unobjectionable. If it be desired, the rollers of any bar h to h^8 or the entire bar may be removed through the openings m^3 and m^{11} , the member m^8 being swung outwardly to remove the closure plate m^9 . In the event that it be desired to substitute a cam having one number of risers for that having another number, the change may be quickly made by removing the section m^4 including its swinging member m^8 and replacing it with another section having a differently shaped cam groove. It will be observed that the section m' in the cam section m is a segment of a true circle, and is of sufficient length to prevent any movement of the numbering head actuating means during and between the inking and printing intervals and that the stop arms q' will always insure the proper positioning of this cam section with relation to the inking mechanism and the impression roller. The cams $m-n$ may be released so as to have rotary movement with the shaft b by merely depressing the levers q . This is desirable when setting the numbering heads, or when the operator has stopped feeding the machine. By using cams having long risers of low pitch, any excessive jars upon the number head actuating plunger and digit wheels are avoided, and the wear thereon from this source and the tendency of the digit wheels to overrun slightly and lose their alinement is avoided. It is not my intention to limit the invention to the details of construction shown in the drawings as such merely illustrate one embodiment of the invention capable of

many changes without departing from the spirit and scope of my invention.

Having described the invention, what I claim as new and desire to have protected by Letters Patent is:—

1. A numbering machine embodying therein a plurality of rotatable drums adapted respectively to carry a set or sequence of numbering heads, a plurality of numbering heads mounted upon said drums respectively, a plurality of independently operative actuating means, rotatable with said drums, each having a circumferentially elongated head acting upon the corresponding numbering head on each of said drums, whereby said numbering heads may be adjusted circumferentially, of said drums, and means common to all of said actuating means whereby they are successively operated to actuate their respective numbering heads, after leaving the printing position and before reaching the inking position.

2. A numbering machine embodying therein a main shaft, a drum adapted to carry a set or sequence of numbering heads mounted upon and rotatable with said shaft, a plurality of numbering heads mounted thereon, cams loosely mounted upon said shaft upon opposite sides of said drum, a plurality of independently operative actuating means rotatable with said drum, each of said means acting upon a numbering head, means whereby said last named means are successively actuated by said cams, movable stops mounted adjacent said cams respectively and adapted to operatively engage same to normally hold them stationary, and means whereby said stops may be actuated to permit said cams to rotate with said shaft.

3. A numbering machine embodying therein a main shaft, a drum adapted to carry a set or sequence of numbering heads mounted upon and rotatable with said shaft, a plurality of numbering heads mounted thereon, cams mounted upon said shaft at opposite sides of said drum, a plurality of independently operative actuating means rotatable with said drum, each of said means acting upon a numbering head, means whereby said last named means are successively actuated by said cams, levers each having a stop-arm thereon, means carried by said cams respectively adapted to engage one of said stop-arms and means whereby said levers may be withdrawn from the operative relation to said cams to permit the rotation of said cams with said drums.

4. A numbering machine embodying therein a main shaft, a drum adapted to carry a set or sequence of numbering heads mounted upon and rotatable with said shaft, a plurality of numbering heads mounted thereon, cams mounted upon said shaft at opposite sides of said drum, a plurality of

independently operative actuating means rotatable with said drum, each of said means acting upon a numbering head, means whereby said last named means are successively actuated by said cams, a lever having a stop-arm thereon adjacent each of said cams, means carried by each of said cams adapted to engage with its respective stop-arm, and a spring projected retard carried by said levers respectively and adapted to be engaged by the means carried by said cams prior to their engagement with said stop-arm.

5. A numbering machine embodying therein a main shaft, a drum adapted to carry a set or sequence of numbering heads mounted upon and rotatable with said shaft, a plurality of numbering heads mounted thereon, a plurality of independently operative actuating means rotatable with said drum, each of said means acting upon a numbering head, cams positioned upon opposite sides of said drum, each of said cams comprising a section having a circular groove segment therein, a removable section having a groove therein containing a riser, and means connecting said section whereby a continuous groove is formed and one removable section may be substituted for another to secure one or more actuations of the numbering heads with each rotation of the drum, and means carried by said actuating means and movably seated in said grooves.

6. A numbering machine embodying therein a main shaft, a drum adapted to carry a set or sequence of numbering heads mounted upon and rotatable with said shaft, a plurality of numbering heads mounted thereon, a plurality of independently operative actuating means rotatable with said drum, each of said means acting upon a numbering head, cams positioned upon opposite sides of said drum, each of said cams comprising a section having a circular groove segment therein, a removable section having a groove therein containing a riser, a swinging member mounted upon said movable section and forming a part of the cam groove, and a plate carried by said swinging member, said cams having an opening therethrough adapted to be closed by said plate whereby said actuating means may be removed through said cams.

7. A numbering machine embodying therein a main shaft, a plurality of drums adapted respectively to carry a set or sequence of numbering heads mounted upon said shaft, a plurality of numbering heads mounted upon said drums respectively, a plurality of independently operative actuating means, rotatable with said drums, each having a circumferentially elongated head acting upon the corresponding numbering head on each of said drums, whereby said

drums may be adjusted axially, and said numbering heads may be adjusted circumferentially, of said drums, a driving gear for said shaft and means whereby said shaft 5 may be disconnected from said gear to permit the movement of said drums independently of said gear.

8. A numbering machine embodying therein a main shaft, a plurality of drums 10 adapted respectively to carry a set or sequence of numbering heads mounted upon said shaft, a plurality of numbering heads mounted upon said drums respectively, a plurality of independently operative actuating means, rotatable with said drums, each having a circumferentially elongated head acting upon the corresponding numbering head on each of said drums, whereby said drums may be adjusted axially, and said 15 numbering heads may be adjusted circumferentially, of said drums, a main driving gear loosely mounted upon said shaft, a disk fixedly mounted upon said shaft adjacent the said gear, and means whereby said disk 20 is adjustably connected with said gear to permit the movement of said shaft independently of said gear and the adjustment of the position of said disk relative to said gear.

9. A numbering machine embodying 30 therein a main shaft, a plurality of drums mounted upon and rotatable with said shaft each of said drums being adapted to carry a set or sequence of numbering heads, and each of said drums having a sequence of 35 openings therethrough, a plurality of numbering heads mounted upon each of said drums adjacent said openings, bars having circumferentially elongated heads mounted in said openings respectively and adapted 40 to have reciprocatory movement toward and away from said numbering heads, guide disks having radially extending slots adapted to receive the ends of said bars, said disks being mounted upon and rotatable with said 45 shaft, and cams positioned upon opposite sides of said disks and adapted to receive the protruding ends of said bars whereby said

bars will receive successive reciprocatory movement actuating said numbering heads after leaving the printing position and before reaching the inking position. 50

10. A numbering machine embodying therein a plurality of rotatable drums adapted respectively to carry a set or sequence of numbering heads, a plurality of numbering heads mounted upon said drums respectively, a plurality of independently operative actuating means, rotatable with said drums, each having a circumferentially elongated head acting upon the corresponding 55 numbering head on each of said drums, whereby said drums may be adjusted axially, and said numbering heads may be adjusted circumferentially, of said drums, the elongated heads of successive actuating 60 means being of gradually increased length and means common to all of said actuating means whereby they are successively operated to actuate their respective numbering heads, after leaving the printing position 65 and before reaching the inking position. 70

11. In a numbering head an actuating means comprising an elongated bar having an enlarged head provided with a curved top, the ends of said bar being provided 75 with anti-friction rollers adapted to be acted upon by a cam.

12. A numbering machine embodying therein a drum a numbering head mounted thereon, means whereby said numbering 80 head will be actuated during the rotation of said drum, and manually operative means acting upon said last named means whereby it may be made inoperative to actuate said numbering head while said drum is rotated. 85

In witness whereof, I have hereunto affixed my signature, in the presence of two subscribing witnesses, this 25th day of February, 1914.

JAMES H. REINHARDT.
